UNITED STATES PATENT OFFICE.

MARION H. COMPTON, OF MUSCATINE, IOWA.

ACETYLENE-GAS GENERATOR.

Original application filed August 3, 1921, Serial No. 489,586. Divided and this application filed December 9, 1922. Serial No. 605,854.

To all whom it may concern:

Be it known that I, MARION H. COMPTON, a citizen of the United States, residing at Muscatine, in the county of Muscatine and 5 State of Iowa, have invented certain new and useful Improvements in Acetylene-Gas Generators, of which the following is a specification, reference being had to the accompanying drawings.

10 This invention relates to acetylene gas generators of that type wherein a container or casing is provided having a spout at its lower end, with a gas bell disposed above the water and carbide receptacle contained 15 within the gas bell and operated by the gas bell to cause the discharge of carbide into the water at the lower end of the container, such a gas generator being illustrated in my pending application for patent, Serial No. 20 489,586, of August 3, 1921, of which application this is a division.

One of the objects of this invention is to provide a generator of this character comprising an outer casing and a hollow pedestal disposed entirely within the casing and removably supported thereon, this pedestal providing a strong, convenient and substantial support for the carbide container and increasing the gas capacity of the machine.

30 A further object is to so construct this pedestal as to provide a sealing compartment exterior to the pedestal having sealing liquid therein and in which the lower portion of the usual gas bell is disposed.

35 Another object is to mount upon the pedestal a gas discharge pipe having in its length a water filter or trap and means being provided whereby the moisture collected in the filter shall be carried back into the main reservoir.

40 Other objects will appear in the course of the following description.

In the drawing:—

45 The figure is a vertical sectional view of an acetylene gas generator constructed in accordance with my invention.

50 Referring to this drawing, 10 designates the outer casing of the generator, which may be any desired length and diameter, the lower end of this casing being formed to provide a relatively deep inverted cone 11. Above the tapered lower end of the casing there is provided an upwardly and inwardly extending flange 12, which at its lower margin is riveted or otherwise attached to

the wall of the casing. The top of the casing is closed by a removable cap or cover 13.

55 The casing, as illustrated, is designed to be disposed beneath the ground, the ground level being indicated by the dotted line *a* so that only the cap 13 is above the ground. This cap 13 is, of course, provided with suitable handles whereby it may be removed and under normal circumstances is locked or otherwise attached to the casing so that it 60 cannot be unauthorizedly removed.

65 Disposed within the upper portion of the casing 10 and resting upon the flange 12 is an annular support or pedestal 14, the lower portion of which is downwardly and outwardly flared at 15, and the lower margin of this portion rests upon the flange 12. It will be noted from the figure that the angle of the flange 12 is slightly greater than the angle of the flared portion 15 so that a 70 wedging fit is secured between the lower margin of the face 15 and the outer face 12, thus securing a tight joint between these parts. The upper portion of the pedestal 14 is of uniform diameter and double-walled so as to provide an outer wall 16, between which and the inner wall an annular sealing space 17 is formed which is to be filled with water or other liquid up to any desired or necessary level. Above the level 75 of the water within this sealing space the pedestal is formed on its inner wall with the perforations 18 whereby gas generated within the generating chamber may escape 80 into the bell.

85 Disposed in the upper portion of the casing 10 is a gas bell 19 having its lower portion disposed within the sealing compartment 17. It will be obvious that this bell 90 will rise and fall in accordance with the amount of gas contained within the bell. The perforations 18 permit the gas to pass from the interior of the pedestal to the interior of the bell. The top of the bell has a handle 20 whereby it may be manually 95 raised. Preferably the upper edge of the wall 16 extends inward at 16^a toward the wall of the gas bell.

100 Disposed within the gas bell and supported by the upper end of the inner wall 16 of the pedestal 14 is a carbide container 105 designated 21. The lower end of this container is hopper-shaped at 22. The upper end of the container is preferably open. A seat 22^a is formed at the upper margin of 110

the hopper-shaped portion 22, the upper end of the inner wall of the pedestal resting within this seat so that the carbide container 21 is properly centered with respect to the 5 casing 10. Obviously there is no necessity of having a gas-tight joint at this point for the reason that any gas which may escape between the inner wall of the pedestal and the carbide container 21 will pass into the 10 bell. Inasmuch as the bottom of the carbide container has the form of an inverted cone, it is obvious that the carbide container will be guided into position as the carbide container is lowered onto the pedestal.

15 I do not wish to be limited in this present case to any particular form of carbide feeding means. I have illustrated, however, part of the carbide feeding means which is shown in my co-pending application, Serial 20 No. 489,586, before referred to. In this construction the lower end of the hopper-shaped portion 22 of the carbide container 21 is formed with a laterally extending chute 23 having side walls and front and 25 rear walls, the bottom 24 of this chute extending downward toward the open lower end thereof.

Pivottally mounted between the side walls 30 is the valve 25 which is crescent-shaped in cross section to provide a downwardly curved portion 26 and a reversely curved portion 27. The chute has a front wall 28, with the lower edge of which the portion 27 of the valve coacts. When the 35 valve is in the position shown in the figure, the hollow interior of the valve is open to receive carbide from the chute. The valve 25 is formed with an arm 30 and when this arm is drawn upward the valve will rotate 40 so that the portion 27 will cause the opening between the walls 24 and 28, while the interior of the valve will discharge downward, thus discharging a certain amount of carbide into the water.

45 In order to operate this valve, I provide operating means disposed within a housing 31 in the main carbide container 21. The operating mechanism comprises a pair of supporting bars 32, and a lever 33 pivoted 50 at 34 between said supporting bars, this lever being connected by a link 35 to the extremity of the arm 30. The inner end of the lever is pivotally connected to a vertically extending rod 36 which extends up 55 through the housing 31, through the upper open end of the carbide chamber, and preferably extends downward through the lower end of the housing and terminates in a tapered extremity located immediately 60 above the opening of the hopper 22. The outer end of the lever 33 carries a weight 37 which holds that end of the lever 33 downward, thus causing the depression of the link 35 and the positioning of the 65 valve to receive carbide from the chute 34.

If the gas in the gas bell becomes reduced in quantity, the gas bell will fall and the upper end of the gas bell will strike the upper end of rod 36, depressing this rod, thus lifting the weight 37 and the link 35, 70 lifting arm 30 and permitting the discharge of carbide from the valve into the generator. When the discharged carbide causes the generation of a certain amount of gas, the bell rises and as soon as it has risen a certain distance the weight 37 will again act to cause the valve to return to the position shown in the figure. The lower end of rod 36 acts to break up the carbide at 75 the lower end of the container.

80 I have shown one form of feeding mechanism, but I do not wish to be limited to this particular form, as it is obvious that the improvements which are claimed in this present application need not be associated with a carbide feed mechanism of the character disclosed.

85 Supported longitudinally within the casing 10 and between the gas bell and the sealing wall 17 is a gas discharge pipe 38, the lower end of which extends into the water contained in the casing 10 above the flange 12. Thus the upper end of this pipe 38 has a branch 39 extending out of the casing. Disposed in the length of the pipe 38 is a filter 40, and connected to the lower end of the pipe 38 and preferably passing below the sealing chamber 17 is a branch 41, which after 90 passing through the inner wall of the pedestal, extends upward into a position just below the hopper-shaped portion 22 and is then downwardly bent to form an inlet terminal 42. When there is an 95 excess of gas, that is when a greater amount of gas is generated than is being drawn off through the pipe 39, the gas will pass upward through the openings 18 into the gas bell and the gas bell will rise, as before stated. When, however, less gas is 100 being generated than is being used, the gas bell will fall, forcing the gas back through the openings 18 into the upper portion of the pedestal and this gas will pass through the inlet 42 and so out through the outlet 39. The filter will cause all moisture and 105 foreign matter to be subtracted from the gas and this moisture will drain back into the sealing space surrounding the flange 12.

110 In order to remove water from this sealing space which surrounds the flange 12 and surrounds the lower end of the pedestal, a draw-off opening closed by a plug 43 may be provided and water may be drawn from the sealing space 17 by opening the 115 plug 44 in the outer wall of this sealing space.

120 In the operation of this construction, the lower portion of the container is filled with water to a point above the upper edge of the 125

- flange 12 and preferably above the lower margin of the downwardly flared conical portion 15 of the pedestal. Thus the joint between the portions 15 and 12 is beneath the water, thus preventing gas from passing around the pedestal or through the joint between the pedestal and the flange 12 into the casing 10. Of course, the carbide chamber is to be filled with carbide and upon a depression of the bell 19 the apparatus will begin to function by discharging carbide into the water, thus generating gas, which will lift the bell 19 to its normal position and the valve will thus be closed. When the gas pressure diminishes, however, the bell 19 will lower, striking the upper end of the rod 36 and causing the discharge of carbide into the water. If it be desired to clean or repair the parts, it is only necessary to take off the cap 13, whereupon the bell 19 may be entirely removed. This discloses the carbide container and the carbide container may be filled with carbide or may be also entirely removed. It is not necessary to remove the pedestal 14 nor withdraw the water within the sealing space 17 or the water exterior to the portions 12 and 15. When sludge is to be removed, a pipe is inserted downward through the casing so that the lower end of the pipe is adjacent the lower extremity of the tapered portion 11 and the sludge may then be pumped off without removing but little of the water within the generator and with but a minimum disturbance of this water. Of course, if it be desired to remove the pedestal also, this may be readily done by lifting it off the flange 12.
- It will be seen that my pedestal is so constructed that it provides a chamber containing water separate and distinct from the main tank, said chamber providing a water seal for the lower end of the gas bell. It is also to be noted that the pedestal is so constructed that it provides a space for the pipe 38, which pipe is provided with a water filter or trap draining back into the water between the parts 12 and 15 and the outer wall of the casing 10. Preferably the upper end of the pipe 38 is provided with a gas cock 45 whereby air may be vented when putting generator into operation after recharging.
- It will be seen that there is a dead air space formed between the wall of the casing 10 and the wall 16 and between the casing 10 and the gas bell which prevents the gas bell seal from freezing.
- I claim:—
1. An acetylene gas generator comprising an outer casing, a pedestal seat attached to the inner face of the casing and extending upward and inward therefrom, a pedestal annular in cross section disposed within the casing and having its lower end detachably resting upon and engaging the seat, said pedestal being formed to provide a liquid holding sealing compartment within the outer casing and spaced therefrom, and a gas bell having its lower portion disposed within the sealing compartment.
  2. A gas generator of the character described comprising an outer casing adapted to contain water in its lower portion and having an upwardly and inwardly extending flange disposed below the water level and constituting a pedestal seat, a pedestal annular in cross section and flared at its lower end to detachably rest upon the exterior face of said flange, said pedestal above the flared lower end being formed to provide an annular sealing compartment within the outer casing and spaced therefrom, and a gas bell disposed within the casing and having its lower portion disposed within the sealing compartment.
  3. An acetylene gas generator comprising an outer casing adapted to contain water and having an upwardly and inwardly extending flange constituting a pedestal seat, the upper end of said flange being disposed below the normal water level in the casing, a pedestal annular in cross section disposed within the casing and having its lower edge downwardly and outwardly flared to rest loosely and detachably upon the upper face of said flange, said pedestal above the flared portion having an outer wall defining a sealing compartment adapted to hold sealing liquid, said outer wall being disposed within the outer casing and spaced therefrom, the upper portion of the pedestal being formed to provide an annular seat, and a carbide container removably disposed within the pedestal and detachably resting upon said seat.
  4. An acetylene gas generator comprising an outer casing adapted to contain water at its lower end and having an upwardly and inwardly projecting flange whose lower edge is disposed below the normal water level in the casing and constituting a pedestal seat, a pedestal having an outwardly and downwardly flaring lower portion loosely resting upon said flange and being disposed within the water exterior to the flange, the pedestal being annular in cross section and extending upward in the casing and spaced therefrom, the pedestal being formed to provide an annular sealing compartment above its flared lower portion disposed inward of and in spaced relation to the outer casing, a gas bell having its lower portion disposed within the sealing compartment, carbide feeding mechanism carried by the pedestal and disposed within the gas bell, and a gas outlet pipe carried by the pedestal between the wall of the pedestal and the wall of the tank, said outlet pipe having a filter in its length and at its lower end draining into the space between the tank and the pedestal supporting flange.
  5. An acetylene gas generator comprising

4

an outer casing adapted to contain water at its lower end and having an upwardly and inwardly projecting flange whose lower edge is disposed below the normal water level in the casing and constituting a pedestal seat, a pedestal having an outwardly and downwardly flaring lower portion resting loosely upon said flange and being disposed within the water exterior to the flange, the pedestal being annular in cross section and extending upward in the casing and spaced therefrom, the pedestal being formed to provide an annular sealing compartment above its flared lower portion within and spaced from the outer casing; a gas bell having its lower portion disposed within the sealing compartment, carbide feeding mechanism carried by the pedestal and disposed within the gas bell, a gas outlet pipe disposed between the pedestal and the wall of the tank and exterior to the bell, said outlet pipe extending vertically and at its upper end having an outlet branch extending through the wall of the tank, the lower end of said pipe discharging into the space between the pedestal supporting flange and the tank, there being a filter between said lower end of the pipe and the discharge branch thereof, and an inlet branch extending from said pipe inward below the gas bell and the sealing compartment. 30

6. An acetylene gas generator comprising an outer casing adapted to contain water at its lower end, a pedestal extending upward within the casing and supported at its lower end thereon, the pedestal being formed to provide an annular sealing compartment above its lower portion, a gas bell having its lower portion disposed within the sealing compartment, carbide feeding mechanism carried by the pedestal and disposed within the gas bell, a gas outlet pipe disposed between the pedestal and the wall of the tank and exterior to the bell, said outlet pipe extending vertically and at its upper end having an outlet branch extending through the wall of the tank, the lower end of the pipe discharging into the space between the pedestal and the tank, there being a filter between said lower end of the pipe and the discharge branch thereof, and an inlet branch extending from said pipe inward below the gas bell and the sealing compartment. 35
